UNITED STATES PATENT OFFICE.

JAMES H. RAND, OF NORTH TONAWANDA, NEW YORK.

INDEX DEVICE.

Application filed February 13, 1922. Serial No. 535,996.

To all whom it may concern:

Be it known that I, JAMES H. RAND, citizen of the United States of America, and resident of North Tonawanda, in the county of Niagara and State of New York, have invented new and useful Improvements in Index Devices, of which the following is a specification.

This invention relates to index devices of the type having swinging index supports for displaying the classified subject-matter of the indices and more particularly to the type in which the index supports are mounted to swing horizontally upon an upright frame which is capable of turning to present different holders to the front of the device.

The principal objects of the invention are to provide a device of the character referred to which is more compact and which can therefore be used with similar devices in closer spaced relationship, which permits the index holders to swing into closer overlapping relationship in either direction from positions normal to the frame, which supports the index holders in such manner that a greater number of the index holders present their index margins to the view of the operator in certain positions of the frame, in which the index holders swing by gravity into close overlapping relationship in either the normal or the operative positions of the frame or in each of these positions, in which the holders are retained by gravity in overlapping relationship in either direction from positions normal to the frame in the operative position or positions of the frame, and which is generally superior to prior devices of the type referred to, especially when used in a row or battery with similar devices as for example at an information station.

The genus of the invention is illustrated by the concrete embodiment shown in the accompanying drawings, in which,

Fig. 1 is a front elevation of the device in normal position;

Fig. 2 is a front view with the frame turned 90° into one operative position and the index holders swung in opposite directions;

Fig. 3 is a vertical central section on line 3—3 of Fig. 1;

Fig. 4 is a horizontal section on line 4—4 of Fig. 3; and

Fig. 5 is a development of the track upon which the frame turns.

The particular embodiment of the inven-

tion chosen for the purpose of illustration comprises a base B, a frame F rotatably mounted to turn on the base and a plurality of index holders H mounted in rows on opposite sides of the frame. As shown in Fig. 4 the frame is rectangular in horizontal outline and the holders H are pivoted on the frame to swing about axes which are arranged in parallelism and in rows along opposite sides of the frame. The holders may be of any suitable construction and they may be pivoted on the frame in various ways, but as shown in the drawings the holders are provided with vertical rods 1 projecting from the tops and bottoms of the holders respectively into openings 3 in the overhanging top and bottom portions of the frame F.

While the construction of the frame F is not of the essence of the present invention I have shown one preferred construction in detail, this construction comprising a pair of angle bars 21 disposed back to back and welded together at the top and bottom, another pair of similar angle bars 22 similarly arranged at the front of the frame, a channel member 23 welded to the forward edges of the angle bars 22, a similar channel member 24 welded to the rearward edges of the angle bars 21, a top cap 25 welded to the upper ends of the parts 21 to 24 and having its margin turned downwardly and inwardly over the upper ends of these parts, a bottom plate 26 welded to the lower ends of the parts 21 to 24 and having its margin turned downwardly, and a tie piece 5 connecting the parts 21 and 22 together near the upper end of the frame. Stops 27 and 28 may be mounted on the front and rear members 23 and 24, as shown in Figs. 3 and 4 to limit the swing of the end holders H.

The frame F is mounted on the base B by means of a central rod 4 anchored in the base and extending upwardly through the tie bar 5 bridging the space between the front and rear angle bars 21 and 24 of the frame, a nut 8 being threaded on the upper end of the rod 4 to retain the frame on the base. Fast to the base B around the rod 4 is a circular track 9 and fast to the bottom of the frame F is a bracket carrying rollers 10 riding on the track 9.

In one aspect of the present invention the track 9 is provided with depressions in such position that the rollers 10 rest therein when the frame is in the normal position shown

in Figs. 1, 3 and 4, thereby to retain the frame in this position by gravity. The preferred shape of the track is shown in development in Fig. 5, where 11 and 12 indicate the aforesaid depressions. By making these depressions gradually sloping, the frame is returned to normal position by gravity when partially turned in either direction from the normal position. By providing substantially flat portions at 12' and 13 intermediate the depressions 11 and 12 the frame will remain stationary when turned 90° in either direction from the normal position.

15 A cardinal feature of the present invention comprises means for tilting the axes of the index holders H longitudinally of the side of the frame to which they are pivoted, that is, to the rear in the embodiment illustrated, so that the holders will swing by gravity into overlapping relationship, as shown in Figs. 1 and 4 when the frame is in normal position, and to tilt the axes transversely of their common plane when the frame is turned to operative position so that the holders will be retained in overlapping relationship when swung to either side as shown in Fig. 2. As illustrated in the drawings the means for accomplishing this tilting consists in means for tilting the axis of the frame F to the rear, this axis being tilted for example by inclining the base B downwardly from front to rear by means of a foot 14 at the front of the base (Fig. 3).

35 In operation the device is swung from the normal position shown in Figs. 1, 3 and 4 to the right or left approximately 90° to present the index holders on one side of the device to the front. After the frame has been so turned the index holders may be turned to the right or left to display the particular data sought, the index tabs 15 serving to indicate the particular holder upon which any name or other information is to be found.

When using the device for alphabetical lists of names, as for example at an information station in a telephone exchange, the names to be found at the right and left of the device respectively may be indicated by letters on the front of the frame as indicated in Fig. 1. If these letters indicate that the name is on the left-hand side the frame is turned to the right by means of the handle 55 16 approximately 90° and remains in this position without being held by virtue of the rollers 10 resting upon the substantially flat portions 12' and 13 of the track 9. When so turned all of the index holders on the left-hand side will be presented to the front of the device in overlapping relationship with the index tabs 15 lying in a straight row in close juxtaposition. These tabs ordinarily carry initials to indicate the names 60 to be found on each holder and with the

tabs arranged in a straight row squarely before the operator the names sought can be readily located. After locating the particular holder upon which the name should be found the holders overlapping this particular holder are swung in the opposite direction so that the opposing faces of two of the holders are fully exposed as shown in Fig. 2. By virtue of the rearward tilt of the frame the holders are retained in this position by gravity. When the frame is turned back to the normal position the holders automatically swing to the rear by gravity and the device is thus made very compact transversely so that a number of devices may be used in a row in closely spaced relationship, the spacing between Figs. 1 and 2 indicating approximately the distance which the devices would ordinarily be spaced apart.

70 The pivot openings 3 for the holders may be spaced from the center of the device the same distance at the top and bottom or they may be spaced farther from the center at the bottom than at the top thus tilting the axes 75 inwardly at the top. With the axes tilted inwardly the holders will remain in overlapping relationship in either the normal or the operative position of the frame whether or not the axis of the frame is tilted rearwardly, but with the frame axis tilted rearwardly and the holder axes tilted inwardly the rearward tilt and the inward tilt mutually contribute to maintain the holders in 80 overlapping relationship.

85 I claim:

1. An index device comprising an upright frame, means on the frame for supporting a plurality of index holders to swing about approximately vertical axes spaced along one 90 side of the frame, and means for tilting the axes longitudinally of said side so that the 95 holders automatically swing in the same direction into overlapping relationship by gravity.

100 2. An index device comprising an upright frame, means for supporting a plurality of index holders along one side of the frame to swing horizontally into overlapping relationship in either direction relative to positions normal to said side, and means for tilting the axes either longitudinally of said side to retain the holders in overlapping relationship in one direction or transversely of said side to retain the holders in overlapping relationship in both directions.

110 3. An index device comprising a frame, means on the frame for supporting a plurality of index holders to swing into overlapping relationship about approximately vertical axes arranged in a row along the frame, 115 means for turning the frame to present the holders either to the side or to the front of the device, and means for tilting said axes rearwardly when the holders are presented to the side so that the holders swing rear- 120 125 130

wardly by gravity into overlapping relationship.

4. An index device comprising a frame, means on the frame for supporting a plurality of index holders to swing, about approximately vertical axes arranged in a row along the frame, into overlapping relationship in either direction from positions normal to said row, means for turning the frame to present the holders either to the side or to the front of the device, and means for tilting said axes rearwardly when the frame is in position to present the holders to the front thereby to retain the holders in overlapping relationship in either direction to which they are swung.

5. An index device comprising a frame, means on the frame for supporting a plurality of index holders to swing, about approximately vertical axes arranged in a row along the frame, into overlapping relationship in either direction from positions normal to said row, means for turning the frame to present the holders either to the side or to the front of the device, and means for tilting said axes rearwardly when the frame is either in position to present the holders to the side or in position to present the holders to the front, whereby the holders gravitationally swing to the rear when presented to the side and to either side when presented to the front.

6. An index device comprising a frame, means on the frame for supporting a plurality of index holders to swing, about approximately vertical axes arranged in rows along opposite sides of the frame respectively, into overlapping relationship in either direction from positions normal to said rows respectively, means for turning the frame to present the holders on either side of the frame to the front of the device, and means for tilting said axes rearwardly when the frame is turned as aforesaid thereby to retain the holders which are presented to the front in overlapping relationship in either direction to which they are swung.

7. An index device comprising a frame, means on the frame for supporting a plurality of index holders to swing, about approximately vertical axes arranged in rows along opposite sides of the frame respectively, into overlapping relationship in either direction from positions normal to said rows respectively, means for turning the frame to present the holders on either side of the frame to the front of the device, and means for tilting said axes rearwardly when the frame is either in normal position or turned as aforesaid, whereby the holders on each side of the frame gravitationally swing to the rear when the frame is in normal position and to either side when presented to the front.

8. An index device comprising a frame, means on the frame for supporting a plu-

rality of index holders to swing, about approximately vertical axes arranged in approximately straight rows along opposite sides of the frame respectively, into overlapping relationship in either direction from positions normal to said rows respectively, means for turning the frame from normal position to present the holders on either side of the frame to the front of the device, and means for automatically returning the frame to normal position when the frame is only partially turned from normal position.

9. An index device comprising a frame, means on the frame for supporting a plurality of index holders to swing, about approximately vertical axes arranged in rows along opposite sides of the frame respectively, into overlapping relationship in either direction from positions normal to said rows respectively, and a circular track upon which said frame is mounted to turn to present the holders on either side of the frame to the front of the device, said track being arranged to tilt said axes rearwardly in both the normal and the front positions of said holders whereby the holders gravitationally swing to the rear when normally disposed and to either side when presented to the front.

10. An index device comprising a frame, means on the frame for supporting a plurality of index holders to swing, about approximately vertical axes arranged in rows along opposite sides of the frame respectively, into overlapping relationship in either direction from positions normal to said rows respectively, a circular track, rollers on the frame riding on said track, whereby the frame may be turned from normal position to present the holders on either side of the frame to the front of the device, said track having depressions positioned to hold the frame in normal position by gravity.

11. An index device comprising a frame, means on the frame for supporting a plurality of index holders to swing, about approximately vertical axes arranged in rows along opposite sides of the frame respectively, into overlapping relationship in either direction from positions normal to said rows respectively, a base, means for supporting said frame on said base to rotate about an axis tilted rearwardly from the vertical, whereby when the frame is in normal position said holders swing rearwardly by gravity and when the frame is rotated to present the holders on one side to the front the latter swing to either side by gravity.

12. An index device comprising a frame, means on the frame for supporting a plurality of index holders to swing, about approximately vertical axes arranged in rows

along opposite sides of the frame respectively, into overlapping relationship in either direction from positions normal to said rows respectively, a base, and means for supporting said frame on said base to rotate about an axis approximately perpendicular to said base and approximately parallel with said axes, said base inclining downwardly toward the rear, whereby when

the frame is in normal position said holders swing rearwardly by gravity and when the frame is rotated to present the holders on one side to the front the latter swing to either side by gravity.

Signed by me at North Tonawanda, 15 N. Y. this eighth day of February 1922.

JAMES H. RAND.
